UNITED STATES PATENT OFFICE.

GEORGE W. BRYANT, OF NEW YORK, N. Y.

SPRING CONTRACTING AND REMOVING DEVICE.

1,008,694.

Specification of Letters Patent. Patented Nov. 14, 1911.

Application filed February 7, 1911. Serial No. 607,028.

To all whom it may concern:

Be it known that I, GEORGE W. BRYANT, a citizen of the United States, residing at New York city, county of New York, and State 5 of New York, have invented certain new and useful Improvements in Spring Contracting and Removing Devices, fully described and represented in the following specification and the accompanying drawings, forming a 10 part of the same.

This invention relates to tools or devices for contracting springs; and more especially to devices intended for contracting and removing or placing in position the valve 15 springs of explosion engines. Such valve springs, and especially those of automobile engines, are frequently or usually so located that access to them is obstructed by other parts or attachments of the engine so that it 20 is extremely difficult to get proper access to the springs for contracting them for releasing the pressure on the valve stem and removing the valve or for removing the springs or placing them in position. Various 25 attempts have been made heretofore by others to provide tools for placing and removing these springs or for compressing or lifting them to release the pressure on the valve stem, but such tools have been of such 30 shape and size or operated in such a way that they can be used only with great difficulty and inconvenience, and are entirely useless with many styles of engines, and are usually limited in their use to a particular operation 35 such as a mere lifting of the lower end of the spring by raising the disk on which the spring rests to relieve the pressure on the valve stem.

The object of the present invention is to 40 provide a device of this character which shall combine great strength and power with ease of operation and adjustment and such compactness and simplicity of construction and adaptability to being used in different 45 positions and with its parts in different relative positions, that it shall be adapted for convenient use with all styles of engines.

To these ends, the invention consists in the 50 construction and arrangement and combinations of parts in a device of the character referred to as hereinafter fully described and specifically pointed out in the claims.

A full understanding of the invention can best be given by a detailed description of a preferred construction embodying the same, 55 and of some of the many ways in which the device may be used, and such a description will now be given in connection with the accompanying drawings, in which—

Figure 1 is a side sectional view of a preferred form of device embodying the invention showing the parts of the device in open position for contracting or compressing a valve spring separate from the engine, this figure being taken on line 1—1 of Fig. 3 but with the spring omitted. Fig. 2 is a view in elevation looking from the left in Fig. 1, and showing a valve spring engaged by the device ready to be compressed. Fig. 3 is a plan view of the device as shown in Fig. 2. Fig. 70 4 is a detail sectional view taken on the line 4—4 of Fig. 3. Fig. 5 is a side view showing a spring engaged as in Fig. 2, but compressed by the operation of the device. Fig. 6 is a view showing the valve and spring 75 and other parts of an engine and the tool or compressing device in position with its spring engaging member entered between lower coils of the spring and after having been operated to compress the spring to lift 80 the lower end of the spring away from the spring disk on the valve stem, leaving the spring disk, key and valve free to be removed. Fig. 7 is a view similar to Fig. 6, 85 but showing the compressing device in position with the body portion thereof inverted and resting on the engine bed. Fig. 8 is a side view showing the device placed in engagement with a valve spring in position for compressing the spring to remove the 90 spring and spring disk together from the engine. Fig. 9 is a view similar to Fig. 8, but showing the device placed in position for compressing and removing the spring without the spring disk. 95

Referring to the drawings, and first to Figs. 1 to 5, the compressing tool or device comprises an elongated stock or body piece 10, which, as shown, is of tubular or cylindrical form, and a carrying rod or bar 11 100 mounted to move endwise in the bore or guide way of the body piece. The rod 11 has formed on, or rigidly secured to, one end a spring-engaging member 12, the

spring engaging part of which is of U shape or forked so that its two sides or prongs may extend, when pushed into the spring, on either side of the valve stem and is made 5 sufficiently thin so as to be readily entered between the coils of the spring, and the prongs are of sufficient width to enable the member to engage properly springs varying considerably in diameter. The body 10 piece 10 is formed with a longitudinal slot 13 on one side extending from the upper end of the body piece as it stands in Figs. 1 and 2, and the neck of the spring-engaging member 12 is reduced so as to enter this 15 slot to permit the rod 11 to move in the body piece to carry the engaging member 12 toward the lower end of the body piece. The body piece is also provided at its lower end as it stands in Figs. 1 and 2 with an engaging member 15. This member 15 is also of 20 U or fork shape to straddle the valve stem or valve lifting rod, and is made flat and thin and of sufficient size, preferably of somewhat greater surface extent than the 25 engaging member 12, to provide a good support for the lower end of the spring when used as shown in Figs. 2 and 5. For moving the rod 11 endwise in the body or stock piece for causing a relative approaching or 30 separating movement of the engaging members, the carrying rod is formed on the side opposite to the side from which the engaging member 12 projects with teeth forming a rack which is engaged by a 35 gear 17 mounted in a chamber in an extension or enlargement 18 of the body piece. The rod 11 and gear 17 and the engaging member 12 are best made of steel to give the required strength, and the teeth of 40 the rack and gear should be cut accurately for strength and ease of operation. The gear is set in a chamber opening from one side of the enlargement 18 of the body piece, and the gear shaft or bearing stud on 45 one side of the gear extends through and has its bearing in an opening in the wall at the inner end of the chamber, the other end of the chamber being closed after the gear is in position by a disk 19 formed with an 50 opening to provide a bearing for the gear shaft or bearing stud on that side of the gear, as shown in Fig. 4. The ends of the gear shaft project and are squared or otherwise formed for turning engagement by a 55 key or wrench. Having squared ends of the gear shaft project from opposite sides of the body or stock piece of the tool enables the gear to be operated from either side of the tool. A single operating gear as shown 60 gives sufficient power for springs having a pressure up to 250 or 300 pounds and is for use on such springs preferably because of the greater simplicity of construction and quickness of action, but it will be understood 65 that the invention is not to be limited to the

use of a single gear, and that if desired or where necessary for compressing more powerful springs two or more gears for increasing the applied power may be used. In order to prevent reverse movement of the carrying rod 11, and to hold it in any position to which it has been moved in compressing a spring, a stop pawl or detent 20 is provided to engage the teeth of the gear 17 so as to permit the gear to be turned in one 75 direction and to lock it against movement in the opposite direction. This pawl, as shown, is mounted in the upper end of a recess or chamber 21 extending into the body or stock piece from the lower end thereof as it stands 80 in Figs. 1 to 5 and across the gear chamber, as clearly shown in Figs. 1 and 4. The pawl is formed by a block or head which has an engaging tooth beveled on one side and which is fitted to move toward and from the 85 gear in the chamber 21 and is formed with or fastened to a guiding and lifting rod 22 which extends upward through the wall at the upper end of the pawl chamber, the pawl being pressed to duty by a spring 90 coiled on the rod 22. In order to adapt the tool to use in various ways, some of which are hereinafter pointed out, it is desirable that the locking pawl or catch may be set for movement of the gear in either direction. 95 For this purpose, in the construction shown the pawl chamber is made cylindrical so that when the pawl is lifted by means of the rod 22 upward to clear it from the teeth of the gear, it may be given a half turn, as 100 from the position shown in Figs. 1 and 4, and then allowed to come into engagement with the gear teeth again in position to permit the gear to turn in the opposite direction and to hold it against turning in the 105 direction in which it was before free to turn. In assembling the gear and the pawl in the construction shown, the pawl with its spring is first placed in position through the opening at the bottom of the stock or body piece, 110 and then, while the pawl is held up above its engaging position, the gear is placed in its chamber and secured by the disk 19. The end of the pawl rod 22 may be turned over as shown after the pawl is in position, so 115 that by lifting and turning this turned over end from one side to the other the pawl will be shifted to permit the gear to be turned to move the rod 11 in either direction and to lock it against movement in the other direction. 120

It will be seen that the construction, as shown and above described, is such that the carrying rod or rack bar 11 may be placed in the bore of the stock or body piece from 125 either end of the latter, and that in whichever way it is placed in the stock piece it may be operated through the turning of the gear to carry its spring engaging member 12 either toward or from the engaging member 130

15 on the stock piece according to the adjustment of the ratchet 20, and that it will always be locked against reverse movement. It will be seen also that when the ratchet 5 is set to permit movement of the carrying rod in either direction, the rod may be released to be moved in the reverse direction by lifting the rod or pin 22 so as to free the gear from the ratchet.

10 Fig. 2 shows the device with its members 12 and 15 in engagement with a spring separate from the engine ready for compressing the spring, the lower end of the spring resting on the member 15 and the member 12 15 extending between coils of the spring near its upper end. The catch pawl being in position as shown in Figs. 1 and 4, the gear is free to be turned to move the bar 11 downward to cause an approaching movement between the engaging members 12 and 15, whereby the spring will be compressed. Fig. 5 shows the parts in position after such movement and with the spring held compressed. The spring when so compressed 20 may, while held by the tool, be placed in position in the engine about the valve stem and between the spring disk on the stem, and the upper disk or other part against which the upper end of the spring is to engage. 25 30 The catch pawl may then be lifted to permit the engaging members to move apart, such movement being best restrained by the operating key or wrench and stopped before the spring has been allowed to make its full 35 expansion to come into strong pressing engagement with the parts against which its ends bear. The compressing device may then be pulled out from the spring, allowing the spring to complete its expansion and 40 seat itself in operative position.

The engaging prongs of the spring engaging member 12 are for the most satisfactory operation of the device best bent, one slightly upward and one slightly downward, 45 as shown in the drawings (see especially in Fig. 2). The engaging member will thus conform more or less accurately to the pitch of the spring and a better and more even holding engagement with the spring will result. The drawings show the prongs of this 50 engaging member bent for operating on a spring having a right-hand coil. For a spring having a left-hand coil, the bending of the prongs of the engaging member 55 should, obviously, be reversed. The tool will usually be supplied with the prongs of this engaging member standing in the same plane, that is, with the member flat so that they may be bent for use with either a right- 60 hand or left-hand spring, as desired, and more or less, according to the pitch of the spring. In some cases it is desirable also that the downwardly bent prong or arm of the engaging member 12 shall be provided 65 with a notch, as shown at 25, on its under-

side at its outer end in position to register with the upper side of the coil of the spring directly beneath it, so as to more securely hold the engaging member and the spring against relative displacement when the 70 spring has been compressed. Such notch may be filed or cut in the engaging member by the user to fit the particular valve springs with which the tool is to be used, or may be formed in the engaging member as sold. In 75 the latter case, both arms or prongs of the engaging member may be notched but on opposite sides as shown in Fig. 2 to provide for the use of the engaging member either side up. 80

When it is desired to take the pressure of the spring off from the valve stem to permit the valve to be lifted or removed without removing the spring from the engine, the compressing device or tool may be conveniently used as shown in Fig. 6. To use the tool as shown in this figure, the carrying rod is placed in the bore of the body piece from the same end as shown in Figs. 1 to 5, but the stop pawl is turned so as to hold 90 against approaching movement of the engaging members of the tool and to permit separating movement, and the tool, with the engaging members brought to the proper relative position, is inserted to carry its engaging member 12 between the coils of the spring near the lower end of the spring and the engaging member 15 over the adjusting collar 30 on the valve lifting rod 31. The tool is then operated by a suitable key or 100 wrench to cause a separating movement of the engaging members whereby the member 12 will be lifted to compress the spring and to lift its lower end clear of the spring disk 32, as shown in Fig. 6. With the spring 105 held in this position, the disk pin 33 is free to be removed, and the valve and valve stem may be lifted or removed and replaced as desired.

Another way of using the tool for releasing the valve stem from the pressure of the spring without removing the spring from the engine is shown in Fig. 7. As here shown, the rack bar or carrying rod 11 is placed in the bore of the body piece from the 110 other end, and the body piece is turned other side up from the positions shown in Figs. 1 to 6, and the tool is placed in operative position with the body piece resting on the engine bed and the engaging member 12 entered between coils of the spring near the lower end of the spring. The stop pawl having been set to permit upward movement of the rack bar and engaging member 12 when the body is in this position and to prevent 115 downward movement, the gear is then turned to lift the engaging member to carry the lower end of the spring away from the spring disk, as shown, thereby releasing the valve and valve stem as before. The diffi- 120 125 130

culties to be avoided in placing the tool in operative position will determine which of the above ways of using the tool for lifting the lower end of the spring will be preferable.

When it is desired to remove a valve spring, the tool may be used as shown in either Figs. 8 or 9. In both of these figures the rack bar and stock piece are assembled as shown in Figs. 1 to 6 with the stop pawl turned to permit approaching and to lock against separating movement of the engaging members. When placed with the spring-engaging member 12 between upper coils of the spring and the member 15 beneath the spring plate 32, as shown in Fig. 8, the spring and spring disk may be removed together after the tool has been operated to cause a relative approaching movement of its engaging members and compression of the spring. The spring may then be held compressed and returned to position and again released if so desired. By entering the engaging member 15 between lower coils of the spring, as shown in Fig. 9, the spring may be removed separated from the spring disk. If the device is to be used in this way, the lower engaging member 15, being used as a spring-engaging member, should be formed so that it may be readily entered between the coils of the spring.

It will be understood that the tool or device may be used otherwise than as in the examples shown and above referred to, and that the invention is not to be limited to the exact construction and arrangement of parts of the device shown and to which the foregoing description has been mainly confined, but that it includes changes and modifications thereof within the claims.

What is claimed is:—

1. In a device of the character described, the combination of a stock piece, a carrying member mounted to move on the stock piece and having a rack formed thereon, forked engaging members carried one by the stock piece and one by the carrying member, an operating gear mounted in the stock piece in position to engage the rack on the carrying member, and a reversible stop pawl for preventing movement of the carrying member on the stock piece in one direction or the other according to the position of the pawl.

2. In a device of the character described, the combination of a stock piece, a carrying member mounted to move on the stock piece and having a rack formed thereon, forked engaging members carried one by the stock piece and one by the carrying member, an operating gear mounted in the stock piece in position to engage the rack on the carrying member, and a reversible stop pawl formed by a toothed block spring pressed toward the gear and provided with means

whereby it may be moved away from the gear and given a half turn to set it in either of two opposite operating positions.

3. In a device of the character described, the combination of a stock piece having a cylindrical bore, a carrying member to move in said bore and adapted to be inserted therein from either end, forked engaging members carried one by the stock piece and one by the carrying member, and means mounted on the stock piece for moving the carrying member to cause relative approaching and separating movements between the engaging members.

4. In a device of the character described, the combination of a stock piece having a guide way formed therein, a carrying rod to move in said guide way and adapted to be inserted therein from either end and having a rack formed thereon, forked engaging members carried one by the stock piece and one by the carrying rod, an operating gear mounted in a chamber in the stock piece in position to engage the rack on the carrying rod, and a reversible stop pawl for preventing movement of the carrying rod in one direction or the other according to the position of the pawl.

5. In a device of the character described, the combination of a stock piece, a carrying member mounted to move on the stock piece, means for moving the carrying member, and a forked spring engaging member carried by the carrying member and adapted to be entered from the side of the spring between the coils thereof and having its spring engaging prongs set to diverge in the direction in which they are to be entered between the coils of the spring.

6. In a device of the character described, the combination of a stock piece 10 having a guide way formed therein and open at both ends, and having a chamber open to said guide way and a second chamber 21 extending from the end of the stock piece 10 across the first said chamber, a carrying rod 11 having a rack formed on one side thereof and adapted to move in said guide way in the stock piece, a gear 17 mounted in the first said chamber in the stock piece to engage the rack on the carrying rod, a reversible spring pressed pawl 21 mounted in the second chamber in the stock piece to engage the gear, and engaging members 12 and 15 carried by the carrying rod and the stock piece respectively.

7. In a device of the character described, the combination of a stock piece having a guide way formed therein, a carrying rod to move in said guide way and adapted to be inserted therein from either end, engaging members carried one by the stock piece and one by the carrying rod, operating means carried by the stock piece for moving the carrying rod endwise in the guide

way, and means for preventing reverse movement of the carrying rod, said last mentioned means being adjustable to prevent movement of the carrying rod in either direction while permitting movement in the opposite direction with the carrying rod inserted from either end of the guide way.

In testimony whereof, I have hereunto set my hand, in the presence of two subscribing witnesses.

GEORGE W. BRYANT.
